Primary Examiner—Jeffrey D Asch*Assistant Examiner*—Carla Jobe Wright(74) *Attorney, Agent, or Firm*—Banner & Witcoff, Ltd.(57) **CLAIM**

The ornamental design for a handset, as shown and described.

DESCRIPTION

FIG. 1 is a bottom plan view of a handset showing my new design;

FIG. 2 is a right side view thereof;

FIG. 3 is a front view thereof;

FIG. 4 is a left side view thereof;

FIG. 5 is a top plan view thereof;

FIG. 6 is a rear view thereof;

FIG. 7 is a perspective front view thereof; and,

FIG. 8 is a perspective rear view thereof.

The rectangular region shown on the upper half of the front of the handset in FIGS. 3 and 7 represents a display screen.

1 Claim, 3 Drawing Sheets
